PAPER-HANGING MACHINE

James B. McDevitt, Dennison, Ohio

Application November 8, 1939, Serial No. 303,402

6 Claims. (Cl. 91—14)

The invention relates to a machine for use in the hanging of paper and adapted to apply paste to the back face of the paper as the paper is unrolled, trim the edges, and measure the proper length for cutting off each strip so that the paper may be easily removed and applied to side walls or ceiling as desired.

The object of the invention is to provide a light and compact machine which can be easily dismantled for transportation, and which performs all of the operations necessary to unroll the paper, trim the edges, apply an even coat of paste of any desired thickness to the back face of the paper and measure the same the proper length for cutting off, all by the manual operation of a single crank.

A further object is to provide a machine of the character referred to which may be easily and readily opened up to give full access to the interior for installing the paper and filling the paste trough or pan.

Another object is to provide a machine of this character in which the paste is evenly distributed over the back face of the paper by means of a spirally grooved roller and forced toward the center of the paper, preventing any paste from squeezing out at the end of the roll and getting on the pattern of the paper.

Still another object of the invention is the provision of such a paste applying roller or cylinder, which is compactly located and arranged to revolve in the opposite direction to the movement of the paper, so as to insure a proper amount of paste being applied to the paper.

Another object is to rotatably mount the paste control roller in eccentric bearings provided with a lever for adjusting the position of the roller for applying a light or heavy coating of paste upon the paper, as desired.

A further object is to provide a machine of this character in which the working parts may be quickly and easily dismantled or knocked down.

A still further object is the provision of a novel and simple device for measuring the proper length of the paper for cutting off.

Still another object is the provision of means for splitting a strip of paper to any desired width as the same is unrolled and pasted.

A further object is the provision of means for controlling the roll of paper in the machine, comprising rod or shaft slidably mounted through the frame, and located through a spaced pair of disk flanges, one flange being fixed to the adjacent frame member, and the other flange being

movable toward and from the opposite frame member to facilitate installing the paper roll, the movable flange being controlled from the outside of the frame by a spring loaded bar which is operated by a lever, the bar placing tension upon the end of the paper roll.

A still further object is to provide a machine of this character having a carrier or conveyor for drawing the paper out of the machine, being geared to run slightly faster than the rolls, so as to keep the paper under tension.

Still another object is to provide means for adjusting this carrier from a vertical to nearly a horizontal position for measuring different lengths of paper as may be required.

The above objects together with others which will be apparent from the drawings and following description or which may be later referred to, may be attained by constructing the improved paper hanging machine in the manner illustrated in the accompanying drawings in which

Figure 1 is a side elevation of the improved machine showing the same in operation;

Fig. 2, a top plan view of the machine with parts broken away for the purpose of illustration;

Fig. 3, an enlarged sectional view through the machine taken as on the line 3—3, Fig. 2;

Fig. 4, a side elevation of the portion of the machine shown in Fig. 3;

Fig. 5, a transverse section showing the spiral roller for applying an even coating of paste upon the back of the paper;

Fig. 6, a fragmentary sectional view of the eccentric bearing for adjusting the spiral roll; and

Fig. 7, a fragmentary plan sectional view of the paper roll supporting mechanism.

Similar numerals refer to similar parts throughout the several views.

The machine is mounted upon a stand comprising the legs 10 and 11 pivoted together midway of their lengths as at 12, the legs 10 being pivotally connected as at 13 to the frame 14 of the machine and having rollers 15 at their lower ends for resting upon or riding over the floor.

The legs 11 have angular lower ends 16 adapted to rest upon the floor and their upper ends are connected by a cross-bar 17 adapted to fit beneath lugs 18 depending from the under side of the frame 14 of the machine so as to hold the legs in operative position.

When it is desired to collapse or knock down the machine for transporting the same, the tie

rod 17 is disengaged from the lugs 18 and the legs folded beneath the frame of the machine.

The frame may be made of wood or other suitable material, and comprises the spaced side frame members 14 joined by the forward and rear cross members 19 and 20, respectively, the upper, central cross bar 21, and the lower, central cross piece 22.

The paste trough 23 may be detachably connected to the under side of the above described frame, and comprises the side walls 24 having the downwardly curved lower edges to which the curved bottom wall 25 is attached, and the front and rear walls 26 and 27, respectively, the rear ends of the side walls being shouldered, as at 28, to fit over the forward edge of the lower cross piece 22, and latch means, as indicated at 29, may be provided for detachably holding the trough in position.

A roller 30 which may be formed of wood or the like, is fixed upon a shaft 31 journaled in bearings 32 which are formed in the upper edges of the side walls 24 of the paste trough and in the lower edges of the side frames 14.

For the purpose of supporting the roll R, of wall paper, in the machine, a rod or shaft 33 is located through the frame, being journaled through the laterally movable, but non-rotatable disk flange 34, and the stationary disk flange 34a, mounted in opposite side members of the frame. One end of the rod or shaft 33 is provided with a head 33a, against which the forked end of the spring loaded arm 35 is received, a spring 35a normally holding the arm 35 in the position shown in Fig. 7, and urging the movable flange 34 inward so as to place a tension on the end of the paper roll.

A lever 103 is pivoted upon a bracket 104, fixed to the adjacent side of the frame, and provided with a depending lug 105 contacting the inner surface of the spring arm 35, a hand knob 106 being provided upon said lever for pulling the same outward to move the flange 34 outward so as to relieve the tension upon the paper roll and facilitate the removal and replacing of paper rolls, when the rod 33 is withdrawn.

The paper is unrolled from said rod 33 and as indicated at P is drawn over the top of the paste roll 30 so as to apply paste from the trough to the back or under surface of the paper which then passes around a roll 36 fixed upon a shaft 37 journaled in bearings 38 located through the hinged side frames 14a, a sprocket 39 being fixed upon one end of said shaft for driving the roll 36 as will be later described.

A grooved roller 40, preferably provided with oppositely disposed spiral grooves 41 extending from the center toward each end, is fixed upon a shaft 42 journaled in eccentric bearings 43 rotatably mounted through openings 44 in the side frames 14 and provided with levers 45 for adjusting the bearings in order to adjust the position of the roll 40 toward or from the roll 36 so as to evenly spread the paste in a film or coating of any desired thickness entirely across the back or under surface of the wall paper.

The side frames 14 have their upper forward portions cut out as at 46 to receive the hinged side frame members 14a, which are connected together at their upper rear corners as by the cross bar 47, hinges 47' connecting said cross bar to the cross bar 21 of the frame.

A hinged frame comprising a pair of inverted L-shaped side members 48, hinged at their lower ends to the forward lower corners of the side

frames 14 as at 13 and connected at their upper ends by a cross piece 50, is adapted to engage over the forward ends of the hinged frame members 14a.

5 A pair of rearwardly extending metal arms is connected to the L-shaped arms 48 and provided with pivoted locking members, 52 adapted to engage the angle irons 53 fixed upon the upper edges of the hinged frame members 14a to lock the L-shaped frame in position, as shown in Figs. 1 and 3.

10 A pair of links 54 is pivoted as at 55 to the arms 51 and at their ends they are connected by a cross bar 56 provided with a hand grip 57 by means of which the links may be swung upon the pivots.

15 The forward edge of this cross bar comprises a straight edge 58 and a hold-down roller 59 is journaled between the links 54.

20 For the purpose of trimming the usual margin from each side of the wall paper a pair of adjustable disk knives 60 is provided, one knife being adapted to trim each margin.

25 These disk knives are mounted upon blocks 61 slidably located upon the rod 49. A leaf spring 62 being provided for placing tension upon each block to cause the disk knife carried thereby to be urged into contact with the metal surface 36a of the roller 36. The upper end of each spring 62 is connected to a bolt 63, the head of which is located within a T-shaped transverse groove 64 in the cross bar 50, a nut 65 being provided for holding the same in adjusted position.

30 If it is desired to split the wall paper to form a narrow strip of any desired width a disk cutter 66 may be provided, being carried upon a block 67 slidably mounted upon the rod 49 and provided with a spring arm 68 having an angular upper end 69 terminating in the downturned lip 70 adapted to engage over the ledge 71 upon the cross piece 50 and provided with a knob 72 for operating the same.

35 A relatively narrow roller 73 may be carried in a bracket 74 supported upon the cross piece 50, said roller being adapted to hold the strip of wall paper in contact with the upper side of the roller 36.

40 A conveyor is mounted upon the machine and comprises a pair of side frame members 75 between the lower ends of which is journaled a roller 76 mounted in open bearings 77 fixed to the upper edges of the side frames 14, curved bars 78 being hingedly mounted upon said bearings and adapted to be normally located in the position shown in Figs. 1, 3 and 4 for retaining the roller in the bearings.

45 A sprocket 79 is fixed upon the roller 76 and connected by a sprocket chain 80 with the sprocket 39 upon the roller 36. A hand crank 81 is connected to the sprocket 79 for manually rotating the same.

50 A roller 82 is carried at the upper end of the conveyor in bearings 83 adjustable by means of the screws 84 and an endless belt 85 is located over the rollers 76 and 82.

55 The conveyor is adapted to be adjustably mounted at any desired angle by means of the U-shaped rod 86 connected at its upper ends to the upper portion of the side frames 75, by an adjustable connection indicated generally at 87, the lower end of the U-shaped rod being adapted to be received by the lugs 88 at the lower rear corners of the side frames 14 or against the stop pins 89 at the upper rear corners of said side frames.

A U-shaped bracket 90 is attached to the upper end of the conveyor by means of brackets 91 and provided in each leg with a series of notches 92 adapted to receive opposite ends of a rod 93 to which one end of the paper strip may be connected as at 94.

For the purpose of matching the strips a depending rod 95 may be connected to one of the brackets 91 as by a screw 96 and provided with adjustable pointers 97.

A weighted spool 98 is provided to cooperate with the pointers 97 to measure the length of a strip as will be later described.

A metal plate 107 may be fixed transversely across the conveyor beneath the straight edge 58 to that by means of a sharp knife or the like the paper strip may be cut off at this point.

For the purpose of rotating the paste roll 30 in the direction of the arrow shown in Fig. 3, sprockets 108 and 109 are fixed upon the shafts of the conveyor roller 76 and the paste roller 30 respectively, and are connected by a chain 110.

In the operation of the machine to paste, trim and measure wall paper, a roll of paper is placed upon the spool 33, as indicated at 34.

Paste is placed in the trough 24 and the end of the roll of wall paper is placed, with the back down over the paste roller 30, between the roller 36 and the grooved roller 40 and then under the roller 73 and hold-down roller 59 and onto the endless belt 85 of the conveyor.

The crank 81 is then rotated in a clockwise direction, rotating the conveyor belt 85 so that the upper side thereof travels upward, rotating the paste roll in clockwise direction so as to apply paste to the back of the strip of wall paper and rotating the roll 36 in a clockwise direction so as to feed the strip of paper upward to the conveyor.

It should be understood that unless it is desired to split the strip of paper, the disk cutter 66 is moved away from the roll 36 by disengaging the spring arm 68 from the cross piece 50.

It should also be understood that the margin trimming disk cutters 60 are properly positioned to trim the margins from the strip of wall paper.

The frame 75 of the carrier, or conveyor is graduated, preferably up to forty inches, for measuring short strips of paper, but for measuring and matching longer strips for side walls and ceiling, the correct length may be obtained by raising or lowering the carrier to the desired adjustment, so that the required length of strip reaches the floor from the cutting-off point. For instance, if an eight foot length is required, for side walls, the carrier is so adjusted that when the end of the paper reaches the floor the paper may be cut off at the straight edge 58, producing a strip eight feet long. By raising or lowering the outer end of the carrier, strips of greater or less length may be accurately measured.

When strips of much greater length are required, the folder is used, as shown in Fig. 1. The paper is then run about six inches beyond the end of the carrier and a rod 93 is inserted under the paper and placed in the outermost notch 92, and the end of the paper is pressed over the rod and against the pasted surface of the strip, as indicated at 94, and the weighted roll 98 is placed on top of the paper, and the paper is run through the machine until the weighted roll reaches the floor, as shown in Fig.

1. This makes a single fold, by which strips of from eleven to fourteen feet may be measured.

To produce longer strips two or more folds may be used, it being possible to accurately 5 measure up to the entire length of a roll, if desired. For a double fold, when the paper reaches the position shown in Fig. 1, a second rod 93 is placed beneath the left hand side of the depending loop of paper and pressed into 10 the next adjacent notch 92 in the folder arms, and the weighted roll 98 is placed on top of the paper, between the end of the carrier and said rod, and the machine is operated as above described. Four such folds may be made, folding 15 the entire roll of paper.

The matching of the paper is accomplished by means of the depending rod 95 and the pair of pointers 97. These pointers may be of different colors for convenience of the operator, one generally being green and the other red. For a straight across match only one pointer is used, but for a drop match the two pointers are used alternately.

Assuming that an eight foot strip is required, 25 the machine should be operated to run out eight feet of paper as above described; then if the place on the margin where it says "Join" is at the cutting-off point 56, the machine is set for a straight across match by locating the green pointer to register with the place marked "Join."

For a drop match pattern the other, or red pointer is then set midway between the points marked "Join," and each pointer is used alternately.

From the above it will be obvious that a very simple, efficient and inexpensive apparatus is provided for quickly, easily and accurately pasting, trimming and measuring strips of wall paper for hanging, and it will be seen that the machine may be easily and quickly dismantled for transporting or storing the same and may be easily assembled and placed in condition for operation.

I claim:

1. A machine of the character described including a frame comprising side members and cross members, one cross member being located at the lower edges of the side members at a point spaced from the forward end of the frame, a paste trough shouldered at its rear end to engage over said lower cross member, means for detachably connecting the forward end of the paste trough to the frame, complementary bearings in the paste trough and frame, a paste roll removably journaled in said bearings, means in the frame for supporting a roll of paper at one side of the paste roll, and a feeding roll at the other side of the paste roll.

2. A machine of the character described including a frame comprising side members and cross members, a paste trough detachably supported at the lower side of the frame, a paste roll detachably mounted in said trough, means in the frame at one side of the paste roll for supporting

a roll of paper, a hinged section of the frame above the trough, a feeding roll journaled in said hinged section and normally located at the other side of the paste roll, a conveyor detachably connected to the frame and means for simultaneously driving the conveyor and said rolls.

3. A machine of the character described including a frame comprising side members and cross members, a paste trough detachably supported at the lower side of the frame, a paste

roll detachably mounted in said trough, means in the frame at one side of the paste roll for supporting a roll of paper, a hinged section of the frame above the trough, a feeding roll journaled in said hinged section and normally located at the other side of the paste roll, a conveyor detachably connected to the frame, means for simultaneously driving the conveyor and said rolls, pivoted arms carried by said hinged section, and a roll carried by said arms and adapted to cooperate with the charging end of the conveyor.

4. A machine of the character described including means for supporting a roll of paper, a paste trough, a paste roll in the trough, a feeding roll beyond the paste roll, an upwardly inclined conveyor, means for driving the conveyor and said rolls to apply paste to one side of the paper and convey the paper upward upon the conveyor, means adjacent to the upper end of the conveyor for attaching the leading end of the paper so that as the paper is fed upward on the conveyor it will form a depending loop, indicating means suspended from the upper end of the conveyor adjacent to said loop, and a straight edge at the lower end of the conveyor for cutting off the paper.

5. A machine of the character described including a frame comprising side members and cross members, a paste trough detachably supported at the lower side of the frame, a paste roll detachably mounted in said trough, means in

the frame at one side of the paste roll for supporting a roll of paper, a hinged section of the frame above the trough, a feeding roll journaled in said hinged section and normally located at the other side of the paste roll, a grooved paste distributing roll journaled in the frame and adapted to cooperate with the feeding roll, a conveyor detachably connected to the frame and means for simultaneously driving the conveyor and said rolls.

6. A machine of the character described including a frame comprising side members and cross members, a paste trough detachably supported at the lower side of the frame, a paste roll detachably mounted in said trough, means in the frame at one side of the paste roll for supporting a roll of paper, a hinged section of the frame above the trough, a feeding roll journaled in said hinged section and normally located at the other side of the paste roll, a second hinged section of the frame at the forward end of the first hinged section, a grooved paste distributing roll journaled in the frame and adapted to cooperate with the feeding roll, a disk cutter adjustably mounted in the second hinged section and adapted to cooperate with the feeding roll, a conveyor detachably connected to the frame and means for simultaneously driving the conveyor and said rolls.

JAMES B. McDEVITT.
